[57] CLAIM

The ornamental design for a faucet spout, as shown and described.

DESCRIPTION

FIG. 1 is a front perspective view of a faucet spout showing our new design;

FIG. 2 is a rear perspective view thereof;

FIG. 3 is a left side elevational view thereof;

FIG. 4 is a right side elevational view thereof;

FIG. 5 is a cross-sectional view taken along line 5—5 in FIG. 3;

FIG. 6 is a cross-sectional view taken along line 6—6 in FIG. 3;

FIG. 7 is a top plan view thereof;

FIG. 8 is a front elevational view thereof;

FIG. 9 is a rear elevational view thereof; and,

FIG. 10 is a bottom plan view thereof.

The broken line showing of the aerator in FIG. 1 is for purposes of illustration only and forms no part of the claimed design.
